UNITED STATES PATENT OFFICE.

ROGER W. DISBRO, OF CLEVELAND, OHIO, ASSIGNOR TO THE W. S. TYLER COMPANY, OF CLEVELAND, OHIO, A CORPORATION OF OHIO.

ELEVATOR INCLOSURE.

Application filed June 16, 1923. Serial No. 645,839.

To all whom it may concern:

Be it known that I, ROGER W. DISBRO, a citizen of the United States, and a resident of Cleveland, county of Cuyahoga, and State of Ohio, have invented a new and useful Improvement in Elevator Inclosures, of which the following is a specification, the principle of the invention being herein explained and the best mode in which I have 10 contemplated applying that principle, so as to distinguish it from other inventions.

The present invention, relating, as indicated to elevator inclosures, is directed more particularly to an improved door construction 15 for elevator doors, the principal purpose of the invention being the provision of elevator doors of different types which shall continuously conceal from the occupants of the elevator car the space between the walls 20 of the elevator shaft and the car, irrespective of the position of the doors. To the accomplishment of the foregoing and related ends, said invention, then consists of the means hereinafter fully described and particularly pointed out in the claims.

The annexed drawing and the following description set forth in detail certain mechanism embodying the invention, such disclosed means constituting, however, but one 30 of various mechanical forms in which the principle of the invention may be used.

In said annexed drawing:—

Fig. 1 is a transverse horizontal view of an elevator inclosure and car in which is incorporated the present invention; Fig. 2 is a similar view showing a modification of the invention; and Fig. 3 is still another similar view, showing a further modification.

In each of the figures there is shown an elevator shaft 1 having walls 2, to which are applied the door casings 3 and ornamental trim strips 4. Doors 5 and 6 (Fig. 1) are mounted to normally close the opening in the wall 2 between the door frames 3, these doors being mounted in the usual manner to move in opposite directions to each other and into a position behind the door frames 3 when wide open to permit entrance to or exit from an elevator car 7 through the entire width of the doorway.

The construction as so far described is a standard elevator construction and has the serious objection that it permits occupants of the car 7 who are at either side of the 55 car to look past the corners 8 of the car

and see the unsightly appearance of the interior 9 of the wall 2. In addition to this, occupants of the car who are in certain positions can look down into the elevator shaft and the fact that there is an opening 60 or space between the doors 5 and 6 in their open positions and the wall of the car detracts from the appearance of the entranceway which is otherwise formed between the door frames 3. 65

I have found that the above objections can be avoided by the addition of vertical channel or angle members 10 mounted adjacent the outer wall of the car 7 at the corners 8 of the opening thereof, these angles 70 being secured either by welding or other means permanently in these positions, as at their top and bottom to the soffit and sill of the inclosure. These angles extend into a close proximity to the doors 5 and 6 and 75 act as sub-jams to effectively conceal the interior of the elevator shaft from the occupants of the car or from persons entering the car through the doorway. In addition to this concealment of the elevator shaft, 80 the use of these members 10 greatly improves the appearance of the entranceway to the elevator car and completes the doorway so that it has the appearance and effect of a completely covered and enclosed 85 vestibule between the corridor of the building and the car itself.

In Fig. 2 I have shown elevator doors 11 and 12, to the ends of which are secured angles 13, and these similar channels or angle members 13 also effectively prevent observation of the interior of the shaft by persons in the car and in the corridor, although they do not present the continuous 90 vestibule effect through the entranceway as do the fixed members 10 described above and shown in Fig. 1. These members 13 extend inwardly toward the car from the ends of the doors 11 and 12 and the provision of flanges 14 thereon enhances the 95 appearance since they extend into very close proximity to the walls 15 of the car 7.

In Fig. 3 I have shown an elevator opening which is ordinarily closed by doors 16 and 17 mounted for movement in the same direction and into the space indicated by the dotted lines 18 and 19, respectively. In this construction one side 20 of the door frame is recessed at 21 to provide for the 100 reception of the two doors, the other side 110

22 of the door frame being of a thickness which brings it close to the wall of the car 23 so that no additional means of concealment is necessary between the car and this 5 wall. With doors of this type a single angle member 24 may be used, this angle member being secured to the inner edge of the forward door 16 and extending into close proximity to the front of the car 23 10 and, of course, this same construction may be used whether two or three doors, or even more, are mounted to move in the same direction toward one side of the car and similarly either of the forms shown in Figs. 15 1 and 2 may be used with two doors or with four or six doors, in which half of the doors move in one direction and half in the other.

Other modes of applying the principle of 20 my invention may be employed instead of the one explained, change being made as regards the mechanism herein disclosed, provided the means stated by any of the following claims or the equivalent of such 25 stated means be employed.

25 I therefore particularly point out and distinctly claim as my invention:—

1. In combination with an elevator inclosure comprising spaced door frames and doors mounted adjacent said frames and 30 cooperating together to normally close the opening therebetween, and a car spaced from said inclosure and having an opening in one side registering with the opening between said frames, of vertical sub-jam 35 means interposed between said doors and said car, said means extending substantially across the space between said doors and the outer wall of said car.

2. In combination with an elevator inclosure 40 comprising spaced door frames and

doors mounted adjacent said frames and cooperating together to normally close the opening therebetween, and a car spaced from said inclosure and having an opening in one side registering with the opening between said frames, of a vertical angle plate mounted on said inclosure between said doors and said car, said plate extending substantially across the space between said doors and the outer wall of said car.

3. In combination with an elevator inclosure comprising spaced door frames and doors mounted adjacent said frames and cooperating together to normally close the opening therebetween, and a car spaced from said inclosure and having an opening in one side registering with the opening between said frames, of vertical sub-jam plates mounted on said inclosure between said doors and said car and in substantial alignment with the openings in said inclosure and car, said plates extending substantially across the space between said doors and the outer wall of said car.

4. In combination with an elevator inclosure comprising spaced door frames and doors mounted adjacent said frames and cooperating together to normally close the opening therebetween, and a car spaced from said inclosure and having an opening in one side registering with the opening between said frames, of an angular plate secured to the outer end of one of said doors, said plate extending substantially across the space between said door and the outer wall of said car, and being in substantial alignment with the openings in said inclosure and car when the door is in closed relation.

Signed by me this 7th day of June, 1928.
ROGER W. DISBRO.
